UNITED STATES PATENT OFFICE.

GEORGES DUVOISIN AND OSCAR THIRY, OF PARIS, FRANCE.

MACHINE FOR WRAPPING ANNULAR AND SIMILAR SOLID ARTICLES.

Application filed July 21, 1926, Serial No. 124,068, and in France March 24, 1926.

The wrapping of certain round or flat articles of annular shape (pneumatic tyres, strip, iron wire, etc.) is generally effected by hand, and consists in winding a protecting band all round the article.

5 A machine for performing this work is, however, known, in which a vertical shuttle encircling, at right angles, the article to be wrapped, carries a spool of paper- or other 10 material and receives a movement of rotation about its centre while the article also turns.

In this machine, it is necessary to modify 15 the position of the members actuating and supporting the article in accordance with the dimensions of this latter, which always turns with the same peripheral velocity. The result is either a wasteful consumption 20 of wrapping material on articles of large dimensions, or insufficient wrapping on small articles. Further, the position of the article to be wrapped does not provide the conditions necessary for good mechanical work, its plane of rotation being rarely at 25 right angles to that of the shuttle; and the centering of the article is doubtful.

The object of the present invention is to 30 remedy these inconveniences, and with this object—whilst retaining the relative right-angle position of the planes of rotation of the shuttle and of the ring to be wrapped—the plane of the ring is no longer vertical, but horizontal; and, in order to obtain a 35 peripheral velocity proportional to the diameter of the ring, the latter rests on radial actuating rollers which, at the same time, ensure accurate centering.

A feature of the invention is that the 40 shuttle is open for the passage of the ring to be wrapped, being actuated by pinion gearing arranged in such manner that there is always at least one of its members in engagement with the rackwork of the shuttle as the gap therein passes said members.

45 An embodiment of the invention is illustrated, by way of example, in the accompanying drawing, in which:—

Figs. 1 and 2 are elevations of the machine;

50 Fig. 3 is a plan of Fig. 1;

Figs. 4, 5 and 6 are respectively a front elevation, profile and plan of the shuttle alone, with its train of actuating pinions and

55 Figs. 7 and 8 are respectively a front ele-

vation and plan of the spools of wrapping material mounted on the shuttle.

As can be seen from the drawing, the machine consists of a frame 1 whereon is mounted a substantially circular channel 2 60 that is cut across to form a gap at 3, and also has part of its periphery cut away at 4 (Fig. 4). In this channel a shuttle 5 is guided for rotation, on the one hand, by rollers 6 having their axes of rotation disposed within the channel 2 and, on the other hand, by the lateral cheeks 7, 8 of said channel. The cheek 7 is solid and carries a frame 9 supporting gear wheels 10, 11, 12, one of which, 10, is the driving pinion. The 70 intermediate pinion 11 simply transmits the movement of the wheel 10 to the wheel 12. The shafts 13, 14 of these two wheels, which are equidistant from the centre of the shuttle 5, carry pinions 15, 16 of the same diameter that turn in the same direction and at the same peripheral velocity, owing to the intermediate pinion 11. Said pinions 15, 16 gear with the external toothed crown 75 of the shuttle 5. The linear distance separating the shafts 13 and 14 is such that when the gap 3' of the shuttle passes by the pinions 15, 16 one at least of these will always be in gear with the rackwork 17. This arrangement dispenses with any means 80 for closing the gap 3 or 3' through which the article 18 to be wrapped is inserted.

The driving pinion 10 may be operated by any means such as, for example, the pulley 19 mounted on its shaft 13, over 85 which pulley is passed a belt 20 that transmits motion from the main shaft 21 fitted with fast and loose pulleys 22 and 23, said belt being guided by pulleys 24 mounted on the frame 1 and on the cheek 7. The arrows 90 indicate the path of the belt 20.

The cheek 8 of the channel 2 is provided with a circular groove 26 for the passage of the shafts 27 of the wrapping spools 28, which are fixed on the shuttle 5. The wrapping strip 29 of paper or other material passes between twin guides 30 (Figs. 7 and 8) and then over a roller 31, with tension spring 32, before being wrapped round the article 18. A tension device of any kind 100 may be applied to the spool 28 to prevent accidental unwinding of the strip 29, which is thus kept in tension all the time.

There may be one spool 28 (Fig. 1), or two (Fig. 7) in diametrically opposite po- 110

sitions. In the latter case the two spools act in conjunction without interfering, one carrying for example, a strip of paper, and the other a strip of cloth (the usual wrapping for pneumatic tyres).

The article 18 to be wrapped is arranged horizontally on radial conical rollers 33, 34, 35, 36 the shafts of which turn in bearings provided in supports on the frame 1. These 10 rollers turn in the same direction and at the same velocity, and their upper edges are horizontal. They accordingly centre the article 18, which is laid upon them, automatically, and cause it to turn at a peripheral 15 velocity proportional to its diameter. Motion is transmitted to the rollers 33, 34, 35, 36 by the driving shaft 21 through sets of gear wheels 38, 39 and 40, 41 guides 42, wheels 43 mounted on the shafts of rollers, 20 and a separate belt for each roller to enable them to turn in the same direction. The mechanism comprising the rollers and their transmission devices is enclosed in a gear case 44, the top wall of which is provided 25 with radial openings 45 through which the rollers project, and with an opening for the passage of the shuttle. It also has suitable stops for retaining the article 18 at the beginning of the wrapping operation.

Reference 46 denotes a toothed rack which, in combination with a pinion 47 on a flywheel 48, having a crank 49, enables the pinions 10, 11, 12 that actuate the shuttle to be thrown out of action when required as when the shuttle is to be brought into position to facilitate the passage of the article to be wrapped through the gap therein.

The machine operates in the following manner:—

40 The annular article 18 to be wrapped being laid on the rollers 33, 34, 35, 36 after being inserted through the gap 3' in the shuttle 5, is centered automatically and rotated at a uniform speed by said rollers. 45 The shuttle is then set in operation (by actuating the flywheel 48) and turns round the annulus, which it envelops with paper or cloth from the spool or spools 28.

50 The respective velocities of the shuttle and article are always in relative concordance, whatever the diameter of the article may be. When the operation of wrapping is finished, the machine is thrown out of action, and the wrapped article removed.

55 It will be understood that the transmission devices illustrated are only by way of example and may be replaced by any other suitable system, numerous practical combinations for obtaining the same results falling within the scope of the invention.

I claim:

1. In a machine for wrapping annular articles, a base, a circular hollow housing supported on and at right angles to the base, said housing being interrupted to form a 65 permanent opening, article supporting and centering elements operating in the plane of one wall of said opening and arranged concentric therewith, an annular shuttle operative within the housing and having an 70 opening corresponding in width to the opening in the housing, roller bearings between the shuttle and the inner wall of the housing, the outer edge of the shuttle being provided with gear teeth, gears supported by 75 the housing and operating through an opening in the outer wall thereof to mesh with the gear of the shuttle, the gears being spaced apart a distance exceeding that of the opening of the shuttle to insure a positive 80 driving connection for the shuttle in all positions thereof, and wrapper delivery means carried by and movable with the shuttle, said means being arranged exteriorly of the housing with their shafts extending 85 through an opening in the side of the housing to engage the shuttle.

2. In a machine for wrapping annular articles, a base, a circular hollow housing supported on and at right angles to the base, said housing being interrupted to form a permanent opening, article supporting and centering elements operating in the plane of one wall of said opening and arranged concentric therewith, an annular shuttle operative within the housing and having an opening corresponding in width to the opening in the housing, roller bearings between the shuttle and the inner wall of the housing, the outer edge of the shuttle being provided with gear teeth, gears supported by the housing and operating through an opening in the outer wall thereof to mesh with the gear of the shuttle, the gears being spaced apart a distance exceeding that of the opening of the shuttle to insure a positive driving connection for the shuttle in all positions thereof, and wrapper delivery means carried by and movable with the shuttle, said means being arranged exteriorly of the housing 95 with their shafts extending through an opening in the side of the housing to engage the shuttle, each of said means including a supply spool and a tensioned guiding spool over which the wrapper is delivered from the supply spool to the article, said tensioned guide spools being arranged in diametrically opposed relation on the shuttle.

Signed at Paris, Seine, France, this eighth day of July, A. D. 1926.

GEORGES DUVOISIN.
OSCAR THIRY.
